Germany; vested in the Alien Property Cus-
todian

Application September 19, 1940, Serial No. 357,504
In Germany January 29, 1939

2 Claims. (Cl. 102—84)

The invention relates to a spring mechanism which releases a firing pin or a similar movable part, for a bomb, torpedo, projectiles, fuses, and the like, in such a manner, that the release takes place only after a certain time, previously adjusted.

In accordance with the invention, a movable device is provided which can be placed under pressure and for which release a time governed locking device is provided.

The construction is preferably such, that a sliding plate is located opposite the housing. This plate contains the releasing lever which is held in a locked position by a movable, preferably pendular locking arm of the housing and which snaps back to its starting position under spring pressure when the locking arm is pressed out of the locking position by a movable part of the mechanism whose motion-time may be adjusted as desired.

A plug, which goes through the casing of the mechanism containing body, as well as through the sliding plate and the housing, thus stopping the running off of the mechanism after it has been placed into position, causes the handling to be simple and without errors. To start the mechanism, one only needs to pull out the plug. It is also a safety device. For, should the mechanism be started prematurely through a defect of any part of the latter or some other cause, the sliding plate would then after the running off of the mechanism, snap downward and so effect the release. This is prevented by the plug, which makes a displacement of the plate, carrying the release member impossible.

The plug finally makes it possible to judge whether the mechanism functions properly. If this is not the case and the sliding plate tries to move by itself, it will slide into the notch of the plug. Consequently the plug cannot be pulled out of the mechanism, and thus it is easily discernible, that the running off of the mechanism has started prematurely.

Further features of the invention are, among others, the simple and advantageous guiding, the attachment of the sliding plate to the spring mechanism housing and the arrangement of special side members, which guarantee an exact seating of the spring mechanism.

The drawings present an illustrated example of the invention in which:

Fig. 1 is a front end view of the new locking device in locked position,

Fig. 2 is a side view of the device,

Fig. 3 is a section taken on line A—A of Figs. 1 and 2,

Fig. 4 is a section taken on line B—B of Fig. 1,

Fig. 5 is a top view of the installed locking device,

Fig. 6 is a front end view partly in section with

the cover plate removed and the front plate of the housing partly broken off and taken on line D—D of Fig. 7,

Fig. 7 is a longitudinal section of the locking device,

Fig. 8 is a front end view of the locking device in the released position, and

Fig. 9 is a section taken on line C—C of Fig. 1 of the fitted locking device with safety plug.

10. The housing of the mechanism consists of a front plate 1, a back plate 2, a round plate 3 and a top plate 4. These plates are joined in the usual and known manner by a beading, or they are mortised or otherwise secured. To increase the 15 rigidity of the housing, the plates 1 and 2 are provided with turned over edges 5 and 6 respectively.

The top plate 4 has arched lobes 9 and 10 at its sides, and the ground plate 3 has correspondingly 20 arranged and formed lobes 11 and 12. These lobes serve to accurately seat the mechanism in the bomb, etc. (See Fig. 5.) The form of the lobes 9, 10, 11, 12 corresponds therefore in every case to the configuration of the inner surface of the body into which the mechanism is to be fitted. For the exact fastening of the locking device in the body, pegs 13 and 14 are provided which fit in 25 corresponding grooves in the body into which the mechanism is to be fitted.

30. The lobes 9 and 10 have slightly upward curved ends (see Figs. 2 and 7) upon which the cover part of the body rests and into which the mechanism is to be fitted. Thereby, the mechanism is pressed down elastically; it is clamped fast, and 35 any longitudinal difference of the mechanism that may exist, is thereby equalized.

Somewhat in advance of the front plate 1 a coverplate 15, movable in the longitudinal direction, is provided.

40. When this plate is longitudinally displaced, the side parts 5 of the front plate serve as guide rails, against which the cover plate 15 with its turned over edges leans. The lobes 11 of the edges 5, projecting through a slit, fasten the coverplate 15. 45. By turning over the ends 18 of the lobes 11 it is possible to fasten the plate 15 to the housing in a manner, which is just as simple as it is secure. At the same time a fastening is made, which can be easily loosened.

50. Springs 19, which are fastened on one side to hooks 20 of the housing and on the other side to hooks 21 of the cover plate 15, or which are respectively attached to their edges 16, tend to pull the cover plate out of the locked position, as 55 shown in Figs. 1 and 2 into the released position, as shown in Fig. 8. The coverplate 15 is thus locked in safety position.

Into the housing 1, 2, 3, 4 a spring mechanism 22 is provided which can be wound by the peg 23 60 through a corresponding hole in the body, even

if the apparatus is set up in the body, into which the mechanism is to be installed.

Gearwheel 24, which turns the anchor wheel 32 over the gearwheels 25, 26, 27, 28, 30 and 31, is mounted on the axle of the spring mechanism 22. The anchor wheel co-acts with an anchor 34, which is arranged to swing on the axis 33, and whose projections 35 and 36 extend alternately into the teeth of the anchor wheel.

A brake lever 37, affixed to swing at 39 on the back plate 2 of the housing and extend above the top plate 4 through an opening 38, serves to brake the anchor, whereby the anchor wheel is stopped and consequently the entire mechanism is brought to a standstill. The braking occurs, when the lever 37 of Fig. 6 is drawn out of the position indicated by the dotted line and into the position indicated by the drawn out line, since thereby the crossbar 40 of the lever 37 rests against the stop 41 of the anchor 34 which prevents the latter from swinging.

Between the frontplate 1 and the coverplate 15, on the axle of the spring mechanism 22 lies the pinion 42 which drives the gear wheel 43. This is formed with a projection 44 or otherwise, which consists preferably of a lobe, which is bent out of the wheel disk, according to the example shown in the drawings. The projection 44 co-acts with a locking device, which will be described. A slit 45 in the coverplate 15 makes possible the unhindered movement of the wheel 43 or the lobe 44.

To the axle 46, which is seated in the frontplate 1 of the housing, a locking device 47 is attached which is capable of swinging. That part of the locking device adjoining the front plate 1 serves as a guide, whereas that part close to the free end of the axle 46 terminates in an arm 48 which projects into the sector of motion of the projection 44.

A spring 49 tends to hold the locking device in a locking position, as seen in Fig. 1. The locking position is attained by a cross piece 50 of the locking device 47, which lies under the projection 51 of the coverplate 15 whereby this is stopped in its downward movement.

The arrangement of the locking device or its centre of motion respectively and the projection 51 of the plate 15 is such, that the downward pulling forces of the spring 49, with which the projection 51 presses against the cross piece 50 results in a torque in the direction of the arrow x and thus acts as a safety device of the locking mechanism. For this reason, the point of application of the projection 51 is displaced laterally against the perpendicular through the centre of motion of the locking device 47.

In order to prevent a premature release of the locking device through faulty handling or otherwise, and additional safety measure is provided. This consists of the plug 54 which according to Fig. 9 is injected into the mechanism, when the locking device is placed into the body, into which the mechanism is built. Its shaft is thereby projected into the hole 53 of the plates 1 and 15 until its collar 55 rests against the backwall into the hole of which the plug 54 projects by means of a thin end peg. The notch 56 of the plug 54 now lies only upon the hole 53 of the coverplate

15. Should the coverplate 15 for any reason whatsoever unexpectedly start to move downward, it will be stopped as soon as its wall rests

in the notch 56. At the same time, it also becomes impossible to pull out the plug 54. Since the plug cannot thus be removed; it becomes clear, that the mechanism is out of order.

The mechanism operates as follows:

The spring 22 is wound by a key tight enough, that the projection 44 moves so far in the direction of the arrow y, that the cross piece 50, under pressure of the spring 49 can move in the direction x to the stop of the projection 51, when the coverplate 15 is moved out of the position according to Fig. 8 into the position of Fig. 1. The mechanism, which is stopped by the brake lever 37, is now placed into the body, for which the apparatus is intended. The plug 54 is now inserted, according to Fig. 9 and the coverpart of the body, into which the mechanism is placed, will be closed, thereby the brake 37 will be swung into the position as indicated by the dotted line, so that the running off of the mechanism is only checked by the plug 54, which prevents the anchor from swinging.

The person who is acquainted with the use of the body into which the mechanism is placed, now winds the spring 22 so far, until the dial, which is arranged above the wheel 43, shows the exact number of minutes after which the running mechanism is to start the release.

At the place of use of the device, only the plug 54 needs to be pulled out, in order to set the mechanism free. In a defective mechanism, it is impossible to pull out the plug, as has already been mentioned, and therefore, accidents due to a premature release of the mechanism are prevented.

After the movement of the mechanism is set free, the wheel 43 turns counterclockwise, until after the set minutes have elapsed whereby the projection 44 presses against the arm 48 of the locking device 47 and then swings it until the crosspiece 50 releases the projection 51 so that the plate 15 snaps downward whereby the firing pin 52 causes the release.

What we claim is:

1. In a device of the character described, a casing having an opening therein, a plate slidably mounted outside said casing and formed with a slot therein, a firing pin carried by said plate, a spring urging said plate to firing position, a movable detent adapted to lock said plate in safety position, an escape mechanism operable after a lapse of a predetermined time for releasing said detent, a lever mounted in said casing and extending through said opening and adapted to be moved, from outside said casing, into contact with said mechanism to lock the same and a removable pin extending through said slot into said casing to a position to engage said mechanism to lock the same, said pin having an intermediate portion of reduced diameter adapted to be engaged by an end wall of said slot on movement of said plate toward firing position to prevent removal of said pin.

2. The device claimed in claim 1 wherein an explosive body is provided and said body is formed with a chamber therein in which said device is mounted and wherein said pin extends through a wall of said chamber.
